UNITED STATES PATENT OFFICE.

DAVID JAMES, OF COFFEYVILLE, KANSAS.

VENDING-MACHINE.

SPECIFICATION forming part of Letters Patent No. 738,685, dated September 8, 1903.

Application filed October 27, 1902. Serial No. 129,016. (No model.)

To all whom it may concern:

Be it known that I, DAVID JAMES, a citizen of the United States, residing at Coffeyville, in the county of Montgomery and State of Kansas, have invented a new and useful Vending-Machine, of which the following is a specification.

My present invention relates to a novel vending-machine, and has for its object to provide a machine of its character capable of effectively separating and delivering cigars supplied to the machine in their original packages or boxes.

It is well understood that cigars are packed in boxes row upon row and that the pressure applied in the process of packing causes them to stick together and to assume various transversely angular shapes. They furthermore assume a more or less irregular arrangement within the box by reason of the fact that in boxes of fifty the rows contain alternately twelve and thirteen cigars, the rows containing the larger number being more closely packed. The result is that besides being of various shapes the cigars are not disposed in the box in vertically-aligned rows. As a consequence of the irregularities of form, size, and arrangement of the cigars and of their tendency to adhere to each other in the original package many difficulties are encountered in the production of a machine for feeding and delivering them one at a time with that certainty which is absolutely essential in coin-controlled vending devices.

To the accomplishment of the object stated I have sought to overcome these difficulties by providing, first, a novel form of means for separating one or more cigars from those in the box and for depositing the cigars thus separated in a chute, from which they are removed by a feed-slide; second, a novel arrangement of devices for loosening the cigars in the chute to prevent the choking thereof, and, third, a novel feed-slide arranged to feed the cigars one at a time from the chute to suitable delivering mechanism without the possibility of having the working of the parts obstructed at any time by reason of the varying sizes of the cigars.

The invention also resides in certain other structural provisions which will appear during the succeeding description of that embodiment

of the invention which for the purpose of this disclosure is illustrated in the accompanying drawings and embraced within the scope of the appended claims.

In said drawings, Figure 1 is a side elevation of my vending-machine with parts of the casing broken away and one side wall of the casing entirely removed. Fig. 2 is a longitudinal sectional view, certain positions of the parts being indicated in dotted lines. Fig. 3 is a front elevation of the machine with the casing in section. Fig. 4 is a rear elevation with the casing likewise in section and with certain parts broken away. Fig. 5 is a top plan view with parts broken away. Fig. 6 is a detail perspective view of the operating mechanism for one of the detaching-plates. Fig. 7 is a detail perspective view of one of said plates. Fig. 8 is a sectional view through one of the plates, showing the manner in which the wing thereof is yieldingly retained; and Figs. 9 and 10 are detail sectional views on the lines 9 9 and 10 10 of Fig. 1.

Like characters of reference are employed to designate corresponding parts throughout the several views.

The machine is inclosed within a casing 1, provided in its top wall with a delivery-opening closed by a hinged flap or cover 2. The frame of the machine includes a pair of vertical side plates 3 and 4, a base 5, secured to the bottom of the casing, a pair of horizontal partitions 6 and 7, a front wall 8, and a vertical partition 9. The horizontal partition 6 extends forwardly beyond the plane of the front wall 8, and the vertical partition 9 is disposed some distance in rear of the front wall and is preferably the downturned front end of the partition 7. This upper horizontal partition 7 constitutes the bottom wall of a receptacle designed for the reception of a cigar-box 10, the original package in which fifty or more cigars are packed. Before the box is placed in the receptacle its front end is removed and its cover thrown back. The retention of the box within the receptacle is effected by a pair of box-retainers or gripper-plates 11, (see Figs. 4 and 5,) formed with vertical shoulders 12, constituting abutments for the front edges of the box sides. These gripper-plates 11 are secured at their rear ends to the side walls of the machine-frame, as in

dicated at 13, and extend forward into close proximity to the front wall of the frame, where they are provided with downward extensions 14, disposed between the partition 9 and the 5 front wall 8. (See Figs. 2 and 6.) The plates 11 are constructed of spring metal, so that they grip the box, and being adjusted laterally in accordance with the width thereof they not only retain said box, but their front 10 ends constitute the adjustable side walls of a chute 15, through which the cigars are dropped (as will presently appear) from the box to a feed-slide 16, designed to convey them one at a time to a supporting-ledge 17, from 15 whence they are delivered to a carrier 18. The feed-slide is provided with an automatically-adjustable pocket 19 for the reception of the cigars, said pocket being defined between the front wall 20 of the rear slide-section 21 and the rear wall 22 of the front slide-section 23, as shown in Figs. 2 and 10. The sections of the feed-slide 16 are slidably supported upon the partition 6, and the side arms 24 of the front section 23 extend along 20 opposite sides of the rear section 21 and are provided with rectangular openings 25, through which extends a transverse shaft 26, connected to the rear slide-section 21 and projecting through cam-slots 27 in the opposite side walls 3 and 4 of the machine-frame. (See Figs. 1, 9, and 10.) The slots or openings 25 in the side arms 24 of the front section are of a length sufficient to provide any desired adjustment of the pocket 19, since 25 it will be evident that when the rear slide-section is moved forward by the pitmen 28, connected to the outer ends of the shaft 26, (see Figs. 1 and 10,) the size of the pocket will be decreased by the forward movement 30 of the wall 22 until said shaft comes into contact with the front ends of the slots or openings 25, when, as will be evident, both sections of the slide will move forward to feed a cigar from the bottom of the chute 15 to the 35 supporting-ledge 17, beyond the front wall 8. Ordinarily, however, the cigar deposited in the pocket of the slide will be too wide to permit the shaft 26 to contact with the front ends of the openings 25; but the effect will be the 40 same, because the front wall of the rear slide-section will engage the cigar and through it will effect the advance movement of the front section of the slide. Thus the width of the pocket is automatically adjustable to accommodate cigars of different shapes and sizes, and the pocket being thus adjusted to fit 45 closely any cigar which may be dropped into it the accidental delivery of more than one cigar will be prevented. Besides this relative 50 movement of the two slide-sections in the direction of the forward travel of the slide I have provided for a limited rise and fall of the rear section. It will be observed that in the event of a comparatively small cigar being dropped into the pocket of the slide its upper side would lie in a plane below the top 55 of the feed-slide. If now a second cigar

should rest upon the one in the chute, the rear wall of the pocket would be disposed behind the upper or second cigar, and the latter upon 70 the advance movement of the slide would be clamped against the front wall 8 or against the other cigars interposed between said second or upper cigar and the front wall. This would of course arrest the movement of the 75 slide and interfere with the proper operation of the machine. To prevent this, it is necessary for the top of the rear slide-section to be depressed below the upper edge of the smallest cigar capable of being fed to the pocket; but 80 if the section should be maintained permanently in this depressed position a similar difficulty would be met in the return stroke of the slide—that is to say, if a comparatively large cigar should drop into the pocket during 85 the backward movement of the slide it would project above the top of the rear slide-section. A second cigar resting upon the top of the rear slide-section in rear of the pocket would thus be caught between the upwardly-90 protruding cigar in the pocket and the back wall 9 of the chute, thus obstructing the return movement of the slide and preventing the proper operation of the machine. To overcome these possible obstructions, the cam-slots 27 are so constructed that shortly after 95 the advance movement has begun the rear slide-section, which, as before stated, is fixed to the shaft extending through the slots, will begin to descend, so that it will be depressed below the upper edge of the cigar in the pocket, and thus prevent a superimposed cigar from 100 being caught between the wall 22 of the rear slide-section and the front wall of the chute 15. As will be noted from the form of the 105 slot in Fig. 1, this downward movement of the rear slide-section continues until the rear wall of the pocket has advanced to a point adjacent to the front wall 8, at which time the rear section rises again to close 110 the space which would otherwise be formed at the lower edge of the front wall, and with the parts thus disposed the slide continues its forward movement to deposit the cigar upon the ledge 17. The reverse of the 115 described movement will take place during the retraction of the slide. The rear section, connected to the shaft 26, will move back a slight distance independently of the front section, the shaft 26 traveling from one end 120 to the other of the slots 27. (See Fig. 10.) This will increase the width of the pocket, and the two sections of the slide will move back in unison. As soon, however, as the front end of the rear section passes the front 125 wall it will descend and will almost immediately begin an ascent as the shaft begins to travel up the comparatively long inclined portions of the slots 27. If, therefore, a comparatively large cigar is lodged in the pocket 130 and another cigar is resting on the rear slide-section, the rise of the latter will throw the uppermost cigar upwardly away from its obstructing position in rear of the cigar in the

pocket, and the slide will return with certainty to its initial position. It should be observed in this connection that the slots 25 in the arms 24 of the front slide-section are so proportioned that the shaft 26, to which the rear slide-section is rigidly connected, may have sufficient independent play both horizontally and vertically to provide for those independent movements of the rear slide-section which have been described:

To insure smooth working of the parts, the top wall of the rear slide-section is received within a suitable guide 29, extending between the rear ends of the arms 24 of the front section, and the wall 6 is provided with an elevated rest 30 for the support of the rear wall 22 of the pocket when the slide is in its retracted position, as shown in Fig. 2.

At the lower edge of the ledge 17 is disposed a movable wall 31, constituting part of a holder 32, pivotally supported by a shaft 33 and having a counterweight 34, which normally retains the wall 31 in position to prevent the escape of a cigar from the ledge 17 after it has been delivered thereto by the advance of the feed-slide. From the front of the holder 32 project a pair of trip-arms 35, disposed in the path of a trip-bar 36, movable with the carrier 18, whereby the depression of the carrier will effect the swinging of the holder to withdraw the wall 31 from in advance of the ledge 17, and thus permit the passage of the cigar from said ledge to the carrier in a manner to be explained.

Since the devices for effecting the feed of the cigars from the box or receptacle to the chute 15 and for insuring their proper passage through the chute to the pocket of the slide are intimately associated with and timed for operation in a predetermined order with relation to the movements of the slide, I shall now describe these several devices and the manner in which they are operated, and will then make plain the construction of the carrier and the manner in which it is operated to convey the cigars one at a time to the delivery-opening of the casing and the provision for ejecting the cigars from the carrier upon the arrival of the latter at the point of delivery.

Between a pair of bearing-ears 37, projecting from the front wall 8 of the frame at opposite sides of a slot 38, is pivoted a feed-lever 39, the lower end of which is connected to the front extremity of the feed-slide 16—as, for instance, by having its lower end extended through a loop 40, fixed thereto. (See Figs. 2 and 3.) At a point below the fulcrum of the lever 39 a reciprocatory feed-bar 41 is pivoted thereto, as indicated at 42. The feed-bar is bent, as indicated in Fig. 2, to dispose the major portion of its length in a plane sufficiently above the box of cigars, and the under side of this elevated portion is provided with ratchet-teeth. The feed-bar 41 is passed through a slot 43 in a follower-plate 44, the teeth of the bar engaging with the lower edge

of the slot. The follower-plate 44 is disposed vertically within the box behind the cigars and is pendent from a bearing-sleeve 45, movable upon a rack-bar 46 and provided with a spring-detent 47, engaging with the teeth of the rack-bar to prevent backward movement of the follower-plate. The rack-bar 46 may be mounted in various ways, but, as illustrated in Fig. 2, its front end is preferably secured to the front wall 8 by means of the pintle 48, constituting the fulcrum of the feed-lever, the rear end of the bar 46 being attached to a frame-plate 49, designed to constitute a rear abutment for the box 10 and connected at its opposite ends to a pair of longitudinally-disposed side bars 50, connected at their front ends to the front wall 8 in any suitable manner. It is to be observed that the rack-bar 46, the side bars 50, and the plate 49 constitute a longitudinally-disposed frame, connected at its front end to wall 8, supported at its rear end by the rear end wall of the box 10, and serving as a support for the follower-plate, the plate 49 being slotted to permit the passage therethrough of the rear end of the feed-bar 41. (See Figs. 1, 2, and 4.) Obviously whenever the feed-slide 16 is moved forward it will cause the feed-lever 39 to be swung and the feed-bar 41 to be drawn endwise for the purpose of advancing the follower-plate 44. As the plate advances the detent 47 will engage the next succeeding tooth of the rack-bar 46 to prevent rearward movement of the plate, and as the feed-slide 16 is retracted the feed-bar 41 will be moved rearward independently of the follower-plate to bring a succeeding tooth into engagement with the latter. As the operation is repeated the follower-plate will be advanced step by step to insure the delivery of the cigars from the box, the length of the teeth of the feed-bar 41 being such as to require several advance movements of the follower-plate to effect its progression a distance equal to the width of a cigar, since the feed of the plate the distance of one cigar will expel the end cigar of the bottom row and such others as may be supported by it.

It has been mentioned heretofore that the cigars are packed so closely in the box that they constitute, in effect, a solid body, and therefore it frequently happens that when the follower-plate is advanced sufficiently to cause the first vertical row of cigars to be fed beyond the end of the box they will not detach themselves by their own weight, this tendency of the cigars to cling together being further augmented by their somewhat irregular arrangement, the several cigars of the advanced row being supported more or less by the cigars in rear thereof. I have therefore provided what may be termed "detaching mechanism," which as one or more cigars are advanced to the chute 15 will effect their detachment from the body of cigars in the box. This detaching mechanism in the present embodiment of the invention comprises a pair

of detaching-plates 51, mounted upon the inner faces of the gripper-plates 11 in advance of the abutments 12 for the front of the box. The plates 51 are designed to have reciprocating motion toward and from the front of the machine and are provided with vertically-disposed pivoted wings 52, normally held in the position shown in Fig. 7 by springs 53. When the detaching-plates are retracted or moved toward the rear, the wings are designed to come into contact with the ends of the cigars about to be delivered to the chute. When the wings thus engage the cigars during the retraction of the plates, they yield against the resistance of the springs 53 and lie flat against the inner faces of the plates, as indicated in dotted lines in Fig. 8. Having passed in rear of the reduced ends of the cigars, however, the wings will spring back to their outstanding positions and as the plates are moved forward will engage and detach the cigars, the folding of the wings in the reverse direction being prevented by stop-lugs 54, integral with said wings and disposed to bear against the face of the adjacent detaching-plate, as indicated in Figs. 7 and 8. These detaching-plates are designed to be retracted during the final portion of the advance movement of the feed-slide, and likewise during the advance movement of the follower-plate, and to be moved forward to effect the detachment of the cigars during the final portion of the retractile movement of the slide, at which time the follower-plate is at rest. To effect such movement of the detaching-plates, they are connected to slides 55, movable in guide-slots 56 in the plates 11, and to these slides are connected the upper ends of levers 57, fulcrumed upon the plates 11 (see Fig. 6) and having their lower extremities connected to rearwardly-extending pitmen 58. Each pitman is provided at its rear end with an angular extremity 59, received by a guide-loop 60, upstanding from the rear section of the feed-slide, the disengagement of these ends 59 from the guide-loops being prevented by guards 61. When the feed-slide is in its completely-retracted position, the detaching-plates will be at the limit of their advance movement, as shown in Fig. 2. If now the slide is moved forward, it will not effect the movement of the plates until the rear ends of the guide-loops come into contact with the ends 59 of the pitmen 58, when, as will be evident, the pitmen will be moved forward, the levers 57 will be swung, and the detaching-plates will be retracted during the final advance movement of the feed-slide. Similarly the advance of the detaching-plates will not be effected until the retractile movement of the feed-slide has progressed sufficiently to bring the front ends of the guide-loops 60 into engagement with the ends of the pitmen, at which time the pitmen will be retracted to swing the levers 57 in the reverse direction, and thereby effect the advance of the detaching-plates to detach the front row

of cigars or such of said cigars as may be engaged by the wings as the slide completes its retractile movement. The action of these detaching-plates is ordinarily effective to cause the proper detachment of several cigars and their delivery to the chute 15. It sometimes happens, however, particularly in detaching the first or last rows of cigars in a box, which are approximately straight, that the four cigars constituting such row will be detached from those in the box, but will stick to each other, and instead of dropping into the chute from the end of the box will tilt or swing, the upper cigar striking against the front wall of the chute before the lower cigar of the row is completely discharged from the box, thus bringing the cigars across the top of the chute. This is of course objectionable, as it interferes with the regularity of the feed and tends to clog the chute. To overcome this difficulty, I provide a flexible guard 62, located just in advance of the box and comprising a series of transverse strips connected by links, as shown in Fig. 2. The guard 62 is pendent from a rod 63, adjustably supported by the bars 50, provided with upstanding brackets 64, each of which is formed with a horizontal series of openings 65 for the reception of the ends of the rod 63. The provision of these openings in the brackets enables the flexible guard 62 to be supported at any desired distance from the end of the cigar-box. As a vertical row of cigars is detached by the detaching-plates they will be brought into contact with this guard, which will prevent them from being swung out in the manner described and will compel the row to drop vertically into the chute. Having thus assured the proper delivery of the cigars from the box to the chute above the feed-slide, it becomes necessary to prevent the choking of the chute. This most frequently results from the assumption of such positions by two or more cigars as will prevent them from dropping properly when the pocket of the feed-slide is presented in position under the chute. This character of obstruction is obviated by the provision at the front side of the chute of a vertically-reciprocating loosening-plate 66, provided with ears 67, extended forwardly through slots 68 in the wall 8 and connected to the upper extremities of an inverted bail 69, connected at its lower end to the front edge of the feed-slide, as indicated at 70. Thus as the slide is advanced this plate will be moved downwardly and such cigars as rest against it will be rolled or turned, a similar effect being produced as the plate is elevated by the retraction of the slide. This moving of the cigars adjacent to the front side of the chute will effect the loosening of the cigars above the feed-slide to insure the delivery of one of them to the subjacent pocket. There is a still further possibility of derangement due to the peculiar characteristics of cigars, which, while more or less remote, must nevertheless be taken into consideration and pro-

vided for. The elevation of the top wall of the front feed-slide section is designed to be such that the largest cigars to be handled will not project above it. The peculiarly 5 irregular shapes assumed by packed cigars, however, renders it possible for a cigar to lie in such position in the pocket that its abnormal width in one direction will cause it to protrude above the front section of the slide, and in this unusual event a cigar would perhaps be caught between this projecting portion of the cigar in the pocket and the front wall of the chute. I therefore terminate the 15 wall 8 at some distance from the top of the slide and close the space thus produced by what may be termed a "swinging" buffer-plate 71, so termed because when struck by a cigar advanced in the manner stated it will yield not forwardly to any considerable extent, but vertically, so that the cigar will be rolled back over the cigar projecting upwardly from the pocket. This buffer-plate 20 71 (shown in section in Fig. 2 and in plan in Fig. 5) is provided with a pair of forwardly-extending arms 72, pivoted at their front ends to bearing-brackets 73, projecting from the front wall 8, the axis of movement being located near the horizontal plane of the lower edge of the plate 71. Should a cigar be forced 25 against this plate, the pressure will cause said plate to swing upwardly, causing the cigar to be rolled back in an obvious manner. It is necessary, however, to maintain the closure of the opening below the edge of the wall 8 30 while the buffer-plate 71 rises. I therefore mount in rear of the plate 71 a swinging guard-plate 74, having forwardly-extending arms 75, mounted on a pintle 76, common to the arms of both plates 71 and 74. The arms 35 75 are provided with ends 77, extended forwardly beyond the axes of movement of the two plates and disposed to rest upon the front end of the feed-slide when the latter is in its extreme forward position, so that the guard-plate will be held down close to the top of the rear slide-section, which in this position of the parts will be located directly under the plate. As the slide is retracted the front end thereof riding under the rear portions of the 40 50 arms of both plates will raise them, so that when the feed-slide is completely retracted the plates will rest upon the top of the front section thereof.

Having now described the feed slide and the various adjunctive feeding devices for insuring the proper feed of the cigars from a box to the slide and their delivery from the slide to the carrier, I shall now proceed with the description of the carrier and of the mechanism 55 associated therewith for effecting its movement and the ejection of the cigars therefrom. The carrier (indicated as a whole by the numeral 18) is intended, as stated, to convey cigars one at a time from the machine to the delivery-opening in the casing, where they are discharged and delivered to the vendee. The carrier comprises a support 78, extending

transversely across the machine in front thereof, and pivotally secured as indicated at 79, to the front ends of a pair of swinging 70 arms 80, located at opposite sides of the machine-frame and having pivotal connection at their rear ends therewith adjacent to the upper rear corners thereof. As the support 78 is designed to support the cigar during the 75 movements of the carrier, it is essential that it should be maintained in an approximately horizontal position during its movement. This end is accomplished by forming the support with pendent arms 81, to which are pivoted, as indicated at 82, the front ends of the swinging rods 83, having pivotal connection at their rear ends with the opposite side walls of the machine-frame at points directly below the pivotal connections of the arms 80. To 80 85 facilitate the ejection of the cigars from the support when the latter reaches the discharge or delivery opening, it is desired to tilt said support somewhat, and for this reason the distance separating the axes of movement of the arms and rods is slightly greater than the distance separating their front ends—that is to say, while the arms 80 and rods 83 are disposed nearly parallel they diverge slightly toward their rear ends, and therefore while 90 the support is maintained in an approximately horizontal position it is slightly tipped or tilted as it reaches the point of delivery.

Upon the support 78 is mounted a transversely-curved ejector-plate 84, hinged at its 100 front edge to the support and provided with trip-arms 85, which extend above and in front of the hinged connection. When the carrier comes to rest in the position shown in Fig. 2 of the drawings, the rod 36, contacting with 105 the trip-arms 35 of the holder 32, swings said holder and depresses the wall 31 below the plane of the ledge 17, permitting the cigar to drop from said ledge into the ejector, which normally rests upon the support, as shown. 110 The carrier is then swung upwardly in a manner to be described, presenting the cigar at the delivery-opening in the top wall of the casing. As the carrier reaches this position the trip-arms 85 of the ejector are brought into 115 contact with the wall of the casing and further upward movement of the carrier will cause the ejector to be tilted as it passes through the delivery-opening. The effect of this tilting of the ejector will be to lift the 120 hinged cover 2 and to eject the cigar upon the top of the casing in advance thereof. The carrier then descends and the ejector and cover drop back to their normal positions in an obvious manner.

We now come to consider the construction and operation of the operating mechanism by means of which the carrier is made to deliver one cigar while another is being advanced to the ledge 17 prior to the return of the carrier 130 to its normal position. It is quite evident that many forms of operating mechanism might be employed; but in the present embodiment of the invention I utilize a two-part

shaft comprising a shaft proper (indicated by the numeral 86) and a surrounding sleeve 87. The shaft 86 is disposed horizontally in rear of the machine and has bearings in suitable supporting-brackets 88. The sleeve 87, which is loose upon the shaft, is provided adjacent to its opposite ends with laterally-extending arms 89, to which are pivoted the rear ends of the pitmen 28 for operating the feed-slide, and the lower ends of a pair of links 90, having their upper ends pivoted to the carrier arms 80 in advance of their rear ends. Obviously, therefore, rotary movement of the sleeve will effect the elevation of the carrier 15 and the advance of the feed-slide 16, various other movable parts of the machine being simultaneously operated by reason of their connection with the slide, as we have already seen.

20 Since the connection between the feed-slide and its operating mechanism has now been described, a further peculiarity in the operation of the slide may be intelligently explained. We have seen how the pocket in the 25 slide is enlarged while the slide is moving back and the carrier is being retracted and how the pocket is contracted while the carrier and slide are executing their advance movements. The peculiarity to which reference 30 is made is the widening of the pocket in the feed-slide just as the latter reaches the limit of its forward movement and while the carrier is being presented at the discharge-opening of the casing. It will be noted that the rear 35 wall of the slide-pocket is in engagement with the cigar by reason of the fact that the pitmen 28 are urging forward the rear section of the slide. When, however, the slide is in its completely-advanced position, the axes of 40 the shafts 86 and 26 and of the pivotal connection between the arms 89 and the pitmen 28 will be in alinement, and as the arms 89 continue to move up beyond this position the pivotal connection between the arms and pitmen will necessarily recede in consequence 45 of the arcuate movement of such connection. This recession will necessarily effect slight backward movement of the rear slide-section, with the result that the pocket in the slide 50 will be slightly widened to insure the dropping of the cigar from the pocket to the ledge 17. Thus at the beginning of the forward movement of the slide the pocket is contracted to grip the cigar, and at the end of such forward movement the pocket is expanded to release the cigar. The necessary movement is imparted to the sleeve through the medium of the shaft 86, which is designed to be connected to the sleeve by a detent 91, pivoted upon 55 the sleeve (see Fig. 4) and having its beak 92 arranged to pass through a slot 93 in one wall of the sleeve and to engage a recess 94 in the shaft. When the detent is in its engaging position, the sleeve 87 and shaft 86 are locked 60 together and the rotation of the shaft will effect a similar movement of the sleeve to operate the machine. At one end of the shaft

is provided, as shown in Figs. 1 and 2, a crank-arm 95, to the wrist of which is connected the rear end of a draw-rod 96. The front end of the draw-rod 96 is connected to an operating-lever 97, fulcrumed in a suitable bearing-bracket 98. The draw-rod is designed to be reciprocated by the manual manipulation of the lever 97, and in order to insure the completion of the throw of the lever in one direction before it is moved back I provide a pivoted detent 99, having ratchet-teeth at its opposite edges designed to be engaged by a projection 100 on the lever. 80 As will be obvious, this detent will dog the lever in either direction until it has reached the limit of its movement, when the projection 100 will pass beyond the end of the detent to permit the latter to swing back. The 85 lever may then be moved in the opposite direction and during such movement will be dogged in a similar manner. Thus the lever having been once actuated to elevate the carrier and effect the delivery of the cigar it will 90 be impossible to again move the lever in this direction until it has been completely retracted for the purpose of again effecting the operation of the machine to supply the carrier with another cigar. 95

To provide for the coin control of the machine thus described, the detent 91 is provided upon its end opposite the beak 92 with a counterweight 101 and at its end opposite the counterweight with an upwardly-extending arm 102, provided with a coin-receiver 103. Normally the counterweight 101 retains the detent in a position in which the beak 92 will not extend into the recess 94 in the shaft 86, and the operation of the operating-lever 97 105 will not, therefore, operate the machine to deliver a cigar. If, however, a coin of the proper value is deposited in the receiver 103, the weight 101 will be overcome and the detent will be moved to connect the shaft and sleeve, 110 the coin thus acting as a weight through the instrumentality of which the machine is coupled to its operating mechanism by the coupling of the members of the two-part shaft, constituted by the shaft and sleeve 86 and 115 87, respectively, as heretofore stated. For the purpose of leading the coin from a coin-slot α in the casing to the receiver I provide a coin chute or race 104, (see Fig. 1,) which terminates immediately above the receiver. 120 It will be evident that when the coin is deposited in the opening α it will pass down the race 104 and drop into the coin-receiver 103. The weight of the coin will move the detent to connect the shaft and sleeve, and as the 125 draw-rod 96 is advanced the shaft and sleeve will rotate. Now as the detent is carried by the sleeve and in turn supports the coin-receiver it is evident that as the machine is operated the receiver will move away from the lower end of the race 104 and will assume a position in which the coin will drop from the receiver, and the parts will be moved back to their normal positions. 130

It will now appear that if a coin is dropped into the race 104 before the receiver has returned to its normal position said coin will drop into the bottom of the casing and will not serve to permit a succeeding operation of the machine. To avoid this contingency, I provide a swinging guard 105, pivoted at its upper end, as indicated at 106, to a bracket 107, upstanding from the lower end of the race 104. This guard is arranged to gravitate into position to close the lower end of the race whenever the coin-receiver is moved away and is moved to its inoperative position by a guard-operating finger 108, extending from the sleeve 87 immediately in advance of the coin-receiver 103. Thus the guard will normally be held away from the end of the race by the finger; but when the receiver moves rearwardly during the operation of the machine the finger 108, also moving with the sleeve, will permit the guard 87 to swing back to guard the lower end of the race, and as the receiver returns the guard will be displaced by the finger 108 to permit the coin to drop into the receiver in an obvious manner.

It is thought that from the foregoing the construction and operation of my vending-machine will be clearly apparent; but while the illustrated embodiment of the invention is believed at this time to be preferable I wish to be distinctly understood as reserving to myself the right to effect such changes, modifications, and variations of the illustrated structure as may be fairly embraced within the scope of the protection prayed.

What I claim is—

1. In a vending-machine, the combination with a chute designed to contain cigars to be vended, of a feed-slide designed to remove the cigars one at a time from the chute and having a pocket, means for conveying the cigars to a point of delivery, said means including a carrier, and means operated during the movement of the carrier toward the point of delivery for contracting the pocket of the feed-slide to grip a cigar and to thereafter expand the pocket to permit of the discharge of the cigar.

2. In a vending-machine, the combination with a chute designed to contain cigars, of a feed-slide provided with a pocket and composed of relatively movable sections, means including a carrier for effecting the transfer of a cigar from the slide to a point of delivery, and means operated during the advance of the carrier for imparting relative movement to the slide-sections to effect the contraction of the pocket in the slide and the subsequent expansion of said pocket to release a cigar.

3. In a vending-machine, the combination with a chute designed to contain cigars, of a feed-slide for conveying the cigars one at a time from the chute, said slide being composed of sections capable of relative movement both vertically and horizontally and disposed to provide an intermediate pocket.

4. In a vending-machine, the combination

with a chute designed to contain cigars, of a horizontal feed-slide comprising separate sections disposed to form an intermediate pocket, the rear section of the slide being movable both horizontally and vertically independently of the front section thereof.

5. In a vending-machine, the combination with a vertically-disposed chute designed to contain cigars or the like, of a horizontal feed-slide comprising slide-sections disposed to define an intermediate pocket, means for advancing the feed-slide, and means operating during such advance movement to impart independent vertical movement to one of the slide-sections.

6. In a vending-machine, the combination with a frame provided with cam-slots, a vertical chute designed to contain cigars, and a feed-slide comprising separate slide-sections spaced to form an intermediate pocket, of a shaft connected to the rear slide-section and extended through the cam-slots in the frame, means for reciprocating the rear slide-section, and means for communicating motion from the rear section of the slide to the front section thereof after predetermined independent movement of the rear section.

7. In a vending-machine, the combination with a frame provided with cam-slots, a vertical chute designed to contain cigars, and a feed-slide comprising separate slide-sections spaced to form an intermediate pocket, of a shaft connected to the rear slide-section and extended through the cam-slots in the frame, means for reciprocating the rear slide-section, means for communicating motion from the rear section of the slide to the front section thereof after predetermined independent movement of the rear section, pitmen connected to the outer ends of said shaft, and means for operating the pitmen.

8. In a vending-machine, the combination with a receptacle, a chute in advance thereof, and a feed-slide for conveying cigars one at a time from the chute, of means for feeding the cigars within the receptacle toward the chute, a detaching device designed to engage and detach one or more cigars from the body of cigars in the receptacle, and means for operating the detaching device and feed-slide.

9. In a vending-machine, the combination with a receptacle, a chute disposed in advance thereof, and a feed-slide for conveying cigars one at a time from the chute, of means for feeding the body of cigars within the receptacle toward the chute, reciprocatory detaching devices located at opposite sides of the chute and having engaging portions disposed to engage the opposite ends of one or more cigars and to detach the same from the body of cigars in the receptacle, and means for operating the detaching devices and the feed-slide.

10. In a vending-machine, the combination with a receptacle, a chute disposed in advance thereof, and a feed-slide, of means for feeding the cigars within the receptacle toward the

- chute, detaching devices disposed to engage and to detach one or more cigars and to deposit them in the chute, an operative connection between the detaching devices and the feed-slide, and means for operating the slide.
11. In a vending-machine, the combination with a receptacle, a chute, and a feed-slide, of means for feeding the cigars within the receptacle toward the chute, detaching-plates located at the opposite sides of the chute and having engaging portions disposed to engage one or more cigars, operating-levers for the detaching-plates, and pitmen having operative connection with the levers and feed-slide, respectively.
12. In a vending-machine, the combination with a receptacle, a chute, and a feed-slide, of means for feeding the cigars within the receptacle toward the chute, detaching-plates located at the opposite sides of the chute and having engaging portions disposed to engage one or more cigars, operating-levers for the detaching-plates, pitmen connected to the levers and having angular ends, and loops mounted on the feed-slide and engaging the angular ends of the pitmen.
13. In a vending-machine, the combination with a receptacle, a chute, and a feed-slide, of means for feeding the cigars within the receptacle toward the chute, reciprocatory plates disposed at opposite sides of the chute, engaging means mounted on the detaching-plates, and means for operating the plates and slide.
14. In a vending-machine, the combination with a receptacle, a chute, a feed-slide, and means for feeding the cigars within the receptacle toward the chute, of detaching-plates located at opposite sides of the chute and provided with spring-urged pivoted wings foldable against the detaching-plates during the movement of the latter in one direction, stops for preventing the folding of the wings in the opposite direction, and means for operating the slide and detaching-plates.
15. In a vending-machine, the combination with a receptacle, a chute, and a feed-slide, of means for feeding the cigars within the receptacle toward the chute, and a guard disposed at one end of the receptacle and designed to facilitate the delivery of the cigars from the receptacle to the chute.
16. In a vending-machine, the combination with a receptacle, a chute, and a feed-slide, of means for feeding the cigars within the receptacle toward the chute, and a flexible guard suspended at one end of the receptacle and adjustable with reference thereto.
17. In a vending-machine, the combination with a receptacle, a chute, and a feed-slide, of means for feeding the cigars within the receptacle toward the chute, reciprocatory detaching-plates disposed at opposite sides of the chute and having engaging portions arranged to engage and detach the cigars, and a flexible guard suspended between the detaching-plates.
18. In a vending-machine, the combination with a receptacle, a chute, a feed-slide, and means for feeding the cigars within the receptacle toward the chute, of means for positively detaching certain of the cigars from the body of cigars in the receptacle to insure the delivery of the detached cigars to the chute, and a loosening device movable within the chute to insure the delivery of the cigars from the chute to the slide.
19. In a vending-machine, the combination with a receptacle, a vertical chute, and a horizontal feed-slide below the chute, of a feeder within the receptacle, horizontally-reciprocatory detaching-plates located at opposite sides of the chute, a vertically-reciprocatory loosening-plate located at the front side of the chute, and means for operating the detaching and loosening plates from the feed-slide.
20. In a vending-machine, the combination with a receptacle, a vertical chute, and a feed-slide, of a feeder in the receptacle, reciprocatory detaching-plates and a reciprocatory loosening-plate in the chute, means for operating said plates from the feed-slide, and a flexible guard suspended at one end of the receptacle.
21. In a vending-machine, the combination with a chute, and a reciprocatory feed-slide designed to convey cigars one at a time from the chute, of a yielding buffer-plate located at the front side of the chute immediately above the feed-slide, and a guard disposed in advance of the buffer-plate.
22. In a vending-machine, the combination with a chute, and a reciprocatory feed-slide disposed to convey cigars one at a time from the chute, of a yielding buffer-plate located at the front side of the chute immediately above the feed-slide, pivoted arms supporting the buffer-plate, and a swinging guard-plate disposed in advance of the buffer-plate.
23. In a vending-machine, the combination with a chute, and a reciprocatory feed-slide disposed to convey cigars one at a time from the chute, of a yielding buffer-plate located at the front side of the chute immediately above the feed-slide, pivoted arms supporting the buffer-plate, a swinging guard-plate disposed in advance of the buffer-plate, and pivoted arms supporting the guard-plate and disposed for engagement with the feed-slide.
- In testimony that I claim the foregoing as my own I have hereto affixed my signature in the presence of two witnesses.
- DAVID JAMES.
- Witnesses:
- JOHN H. SIGGERS,
BLANCHE KALDENBACK.
